UNITED STATES PATENT OFFICE.

JOHN H. SUTTHOFF, OF SEATTLE, WASHINGTON.

INFUSION DEVICE.

Application filed August 23, 1923. Serial No. 658,972.

To all whom it may concern:

Be it known that I, JOHN H. SUTTHOFF, a citizen of the United States, and a resident of Seattle, in the county of King and 5 State of Washington, have invented certain new and useful Improvements in Infusion Devices, of which the following is a specification.

My invention relates to improvements in 10 infusers for brewing beverages and the object of my invention is to provide an infuser of this nature that is neat in appearance, easy to operate, strong, simple and compact in construction, not expensive to 15 manufacture and that is efficient in permitting the extraction of the soluble and aromatic substances from material that may be contained therein.

Another object is to provide an infuser of 20 this nature that is adapted when open to be used as a scoop to dip up material and that is further adapted to serve as a measuring device for measuring the amount of material that is being used, said infuser being arranged to have adjustable measuring apparatus placed therein if desired.

A further object is to provide an infuser comprising a plurality of sections hinged together in such a manner that certain sections 30 are adapted to be swung or rotated within certain other sections to discharge or eject used material therefrom after brewing an infusion.

Further objects are to provide an infuser 35 in which the parts are all secured together so that they cannot be detached from each other and to provide an infuser which is shaped so that the liquid in which it is immersed will quickly and easily penetrate all 40 parts of the material in the infuser.

Other and more specific objects will be apparent from the following description taken in connection with the accompanying drawings.

Before describing the invention in detail I desire to have it understood that the invention is not limited to the particular construction and arrangement of parts which I have illustrated and shall hereinafter describe and that various changes may be made in the mechanism shown without departing from the spirit or scope of the invention and that the phraseology which I employ is for the purpose of description and not for limitation.

In the accompanying drawings Figure 1,

is a view in perspective of a preferred form of infuser constructed in accordance with my invention showing the device closed.

Fig. 2 is a view in cross section of the 60 same substantially on broken line 2—2 of Fig. 1 showing the device open.

Fig. 3 is a view in longitudinal mid-section of the same.

Fig. 4 is a perspective view of a modified form of the invention.

Fig. 5 is a sectional view on broken line 5, 5 of Fig. 4, showing the infuser closed.

Fig. 6 is a sectional view similar to Fig. 5, 70 except that the device is in a horizontal position and is shown open.

Fig. 7 is a sectional view showing another modification of the invention in which one of the side members is flat.

Fig. 8 is a sectional view showing another 75 modified form of the invention in which the infuser is made up of one flat member and two arcuate members that are arranged to slide one over the other.

Fig. 9 is a sectional view of a modified 80 form of the invention in which the infuser is made up of a concave or recessed rear portion and two arcuate front members arranged to slide one over the other.

Fig. 10 is a sectional view of the infuser 85 shown in Fig. 9 as it may appear when fully open.

Fig. 11 is a sectional view of another modified form of the invention which may be similar to the forms shown in Figs. 1 to 90 6, except that the inner member is a segment less than a semi-circle thereby making it more easily cleaned.

Infusion devices of this nature with which I am familiar are usually made in two or 95 more detachable parts which are liable to become separated when not in use and which often become battered and bent up, in washing with other dishes, in such a manner as to render them difficult to put together 100 again. These two part devices are often relatively deep and small, making them comparatively hard to clean and are usually constructed so that they require the use of both hands to put them together. In designing my present infuser I have kept in mind the objectionable features above pointed out and have endeavored to produce a device that will overcome the same.

Referring to the drawings, throughout 110 which like reference numerals designate like parts, I have shown, in Figs. 1, 2 and 3 a

preferred embodiment of my infuser composed of two oval shaped half shells 12 and 13 provided at opposite ends on the line of their major axis with overlapping lugs 14, 5 through which extend pivots 15 that pivotally connect the two half shells together. The half shells 12 and 13 are of comparatively thin but strong perforated metal and one of said half shells 12 is slightly smaller 10 than the other half shell 13 so that said two half shells may be turned one within the other. When the half shells 12 and 13 are in the closed position shown in Fig. 1 the device presents substantially the symmetrical oval appearance of an ordinary foot- 15 ball.

The innermost half shell 12 is provided with a fixedly mounted handle 16 having a shouldered portion 17 arranged to snap over 20 the edge of the outer half shell 13 to hold said two half shell members in the position shown in Fig. 1. If desired a thumb piece 18 may be provided on the exterior of the outer half shell 13 see Fig. 2 to facilitate 25 opening and closing the device.

In filling or charging the infuser the same is opened as shown in Fig. 2 and may be dipped into the material like a scoop or the material may be poured into the inner half 30 shell 12, the outer half shell is then rotated to the closed position and snapped into engagement with the shouldered portion 17 of the handle 16 which is secured to the inner half shell 12. The infuser may then be im- 35 mersed in a liquid until the desired amount of soluble and aromatic substances are extracted from the contents, whereupon it may be removed and opened into the position shown in Fig. 2 and the material contained 40 therein quickly and easily emptied or washed out. The edges of the inner half shell 12 fit the outer half shell 13 snugly so that, in opening the infuser said edges will sweep through the outer half shell and clean 45 the same. The method of filling or charging, just described, insures that the device will never be filled more than half full thereby allowing room for expansion of the material when it becomes wet and also al- 50 lowing for a free circulation of liquid through the material at all times. The oval shape of the infuser tends to permit the liquid to penetrate freely in the shorter di- 55 rections, perpendicular to its major axis. If desired the handle 17 may be long like the handle of a spoon as it may terminate in a hook that will conveniently hook over the edge of a tea cup where the infuser is placed therein.

60 In Figs. 4, 5 and 6, I have disclosed an infuser similar to the one disclosed in connection with Figs. 1, 2 and 3 except that the same is formed of two half shells 19 and 20 of semi-cylindrical, instead of oval shape, 65 pivotally connected on an axial line by pins

21 and arranged to be moved rotatably one within the other between the closed and open positions shown in Figs. 5 and 6 respectively. A handle 22 is provided on the smaller semi-cylindrical shell 19 and ar- 70 ranged to snap over the edge of the larger semi-cylindrical shell 20 to releasably hold said two shells in the closed position. As a means for measuring a quantity of ma- 75 terial in the smaller semi-cylindrical shell 19 I have provided a flat plate 23 having slotted ears 23' which are hingedly mounted on the pivot pins 21 so that the plate 23 may be moved into various adjusted positions said ears 23' being friction bound or 80 being otherwise yieldingly held in such a manner that the plate may be moved by pressure of the fingers but will stay where it is set while material is being dipped or poured into the compartment of which it 85 forms one side. If desired graduation marks 24 may be provided in the inside of the shell 19 to enable the user to set the device to measure any amount, the graduations preferably corresponding to a tea spoon 90 measure. The measuring plate 23 may also be used to aid in cleaning material out of the shell 19 this being accomplished by placing the fingers on the plate 23 and moving the same around within the shell. It 95 will be understood that a similar measuring plate may be used in other forms herein shown but that the same is not necessary to the successful operation of this device.

In Figure 7 I have shown an infuser in 100 which the front is formed of a hollow shell 25 as of oblong, spherical or cylindrical shape, and the back member is formed of a flat plate 26 secured to the shell 25 by pivot pins 27 and having a handle 28 provided 105 with snap member 29 arranged to snap over the edge of the shell 25. The lower edge of the shell 25 is provided with an upwardly bent portion 30 forming a stop for the plate 26. In operation when the shell 25 is turned 110 down into a position as indicated by dotted lines it may be quickly and easily charged as by dipping or pouring material into that portion of the shell in front of the plate 26. After use the shell 25 and plate 26 may be 115 rotated relative to each other to cause the plate to sweep through the shell and eject all used material therefrom.

Figure 8 shows an infuser substantially the same as shown in Fig. 7 except that the 120 front is made of two shells 31 and 32 ar- 125 ranged to slide one over the other and each of substantially one fourth of a circle in cross sectional shape. The back portion in Fig. 8 may be a flat plate identical with the plate shown in Fig. 7 and is connected with shells 31 and 32 by pivots 33. In filling this infuser the shells 31 and 32 may occupy the position shown, thus making a device that is very convenient to grasp and dip into the 130

material. This device is easily and quickly cleaned in the same manner as the device shown in Fig. 7 the flat back member being arranged to make a complete and clean sweep through the inner shell 31 to eject all material therefrom. Figs. 9 and 10 show an infuser having two front shell members 34 and 35 connected with each other and with a back member 36 by pivots 37, the back member being of arcuate shape and having edge flanges 38 and 39. A stop member 40 rigid with the inner shell 34 and engageable with the outer shell 35 is provided for limiting the relative movement of said two shells 15 in one direction. When closed the several parts assume the positions shown in Fig. 9 and when open said parts may assume the positions shown in Fig. 10, in which latter position the arcuate back portion 36 may 20 serve as a receptacle in which a measured quantity of material may be placed. After use material may be ejected from the shell members 34 and 35 by moving shell member 35 downwardly over shell member 34 and 25 then causing back member 36 with flange 37 to sweep through shell member 34.

In Fig. 11 I have shown an infuser comprising two shell members 41 and 42 connected for relative movement one within the other by pivots 43 the outer shell member 42 being of substantially semi-circular cross sectional shape and the inner shell member 41 being of less curvature than the outer shell member and preferably being, in cross 35 section, a circular segment, less than a semi-circle and arranged so that when it is swung into the outer shell 42 it will stand away from the walls thereof. The extremities of the inner shell member 41 are bent outwardly as at 44 to make a close fit with respect to the outer shell member and to facilitate the ejection of used material therefrom in cleaning. One advantage gained by making the inner shell member in this form of infuser less than a semicircle in cross section 40 is, that the same is more easily cleaned than are the corresponding forms shown in Figs. 1 to 6 inclusive, the wet and packed material dropping out or being susceptible to being washed out more easily. Another advantage 45 is that where the inner shell is to be used as a measuring device it may be desired to have the same hold considerably less than the outer shell to allow for expansion of the material that is being used to more than double the original volume when wet.

Infusion devices of the nature hereinbefore described are especially adapted for brewing beverages as tea and coffee and for 50 use as spice boxes which may be placed in vessels of food that are being cooked for flavoring the same.

In the use of a device of this nature for preparing an infusion the material as tea or coffee is first placed in the infuser and said

infuser is then submerged in liquid preferably hot water long enough to permit the dissolving out or extraction of soluble and aromatic matter from the material sufficient to suit the taste of the user, whereupon the infusion is poured off or the infuser removed therefrom. After use the infuser is usually emptied and cleaned before it is used again.

By the term perforated shell members, as herein used I mean any shell members, as of perforated metal, wire mesh or the like, capable of being freely penetrated by a liquid and yet capable of retaining material, as tea or coffee, from which an infusion is to be prepared.

Infusers will preferably be made in various sizes the smaller ones holding only enough material for brewing a single cup of beverage as tea, and the larger ones being of sufficient size to meet different requirements.

The foregoing description and accompanying drawings disclose what I now consider to be preferred embodiments of my invention but it will be understood that these disclosures are merely illustrative and that such changes in the same may be resorted to as are within the scope and spirit of the following claims.

I claim:

1. An infuser embodying a plurality of perforated members pivotally connected for rotary movement one within another and arranged to form a receptacle capable of being penetrated by liquid.

2. An infuser embodying a plurality of perforated members pivotally connected together and arranged to form an enclosure capable of being penetrated by liquid, said members being arranged to be moved one within another to open and close said infuser and to discharge material therefrom.

3. An infuser embodying a plurality of perforated arcuate members pivoted at opposite points and arranged to swing one within another into open and closed positions.

4. An infuser embodying a plurality of perforated members pivotally connected together and arranged to co-operate in forming an enclosure capable of being freely penetrated by liquid, one of said members being arranged to swing within another of said members to discharge material therefrom.

5. An infuser embodying perforated shell members of arcuate cross sectional shape and other members pivoted to said perforated shell members on the central axis of the same and arranged to swing within said perforated shell members.

6. An infuser embodying two perforated shell members of semi-circular cross sectional shape arranged to fit one within the other and pivoted on their common axis for relative swinging movement.

7. An infuser embodying two perforated shell members of semi-circular cross sectional shape pivoted together for relative swinging movement on their common axis and arranged to be moved one within the other and readily releasable means for securing said two shell members together to form a container.
8. An infuser embodying two oval shaped 10 perforated half shells pivoted together on the line of their major axis, one of said half shells being slightly larger than the other whereby said half shells may swing one within the other.
9. An infuser embodying perforated shell members of arcuate cross sectional shape pivoted together for relative swinging movement on a common axis and arranged to be moved one within another and a measuring 15 plate pivoted on said common axis and arranged to be moved into various adjusted positions within one of said shell members.
10. An infuser embodying a plurality of shell members pivotally connected together for relative swinging movement one within another on a common axis, and devices within said shell members arranged to co-operate therewith to form adjustable measuring means.
11. An infuser embodying two half shells 20 pivotally connected on a common axis and arranged to swing one within the other to form a receptacle for infusion material, a handle secured to the innermost half shell and spring means integral with said handle 25 arranged to snap over the edge of the outermost half shell.

JOHN H. SUTTHOFF.
